UNITED STATES PATENT OFFICE.

NIC KRUMP, OF CHICAGO, ILLINOIS.

CROSSOVER AND DOORWAY OPENING FOR SUSPENDED RAIL TRACKS.

Application filed December 28, 1922. Serial No. 609,443.

To all whom it may concern:

Be it known that I, NIC KRUMP, a citizen of the United States, and a resident of Chicago, in the county of Cook and State 5 of Illinois, have invented certain new and useful Improvements in Crossovers and Doorway Openings for Suspended Rail Tracks, of which the following, when taken in connection with the drawings accompany- 10 ing and forming a part hereof, is a specification.

This invention relates to means whereby a trolley will automatically lay a track over an open space, and after the trolley has 15 traveled over said track the track will automatically be removed and said open space restored.

Among the objects of the invention is to obtain a construction whereby, when a 20 rail suspended track is crossed by a like rail suspended track at an angle, an opening in said tracks will be automatically filled by a track section, by a trolley approaching said opening, on either track and 25 in either direction. An additional object is to obtain, in a suspended rail track which extends through a door way, an open space through which the door to said door way may be moved to a closed position, and 30 when said door is in an open position a trolley may travel in either direction on the track and will automatically lay a track across said open space and continue its travel along the track; and when trolley 35 has travelled over and beyond said automatically laid track section, said track section will automatically resume its initial and normal position relative to said open space. Additional objects are to obtain a 40 construction of the kind named which is simple in construction, comprising few parts, economically made, and not liable to break or get out of order.

In installing a construction embodying 45 this invention duplicate members are placed at the ends of the tracks at the open space which is to be automatically bridged by one or the other thereof, determined by the direction in which the trolley is travelling on 50 said tracks, and certain parts on the other one of said members are movable, and are actuated by said trolley, to permit the trolley to pass on in continued travel along the tracks.

55 In the drawings referred to Fig. 1 is a side elevation of an installation embodying

the invention, with one of the rails of the track section removed to expose the view parts positioned between said tracks.

Fig. 2 is a top plan view of a bridging 60 track section forming an element of the installation, in a horizontal position.

Fig. 3 is a view on line 3—3 of Fig 1, on an enlarged scale, viewed as indicated by 65 arrows.

Fig. 4 is a side elevation of a bridging track section, in a horizontal plane, with one of the rails of the section removed to expose to view parts positioned between the rails, with a trolley wheel about to leave 70 said horizontal track section and to pass through an additional bridging section positioned in front of said trolley.

A reference character applied to designate a given part indicates said part 75 throughout the several figures of the drawings wherever the same appears.

A represents a rail approaching an opening in a track, from the left hand side of 80 said opening, as viewed in Fig. 1, and a the end of said rail. A' represents a rail approaching said opening from the right hand side thereof, as viewed in Fig. 1, and a' the end of said rail. B represents a chair on 85 which the ends of rails A, A', adjacent to the opening are supported, being secured there- to by plate b , and bolts b' , b'' . B' represents a similar plate to plate B, at the opposite end of the opening, to which the ends of rails A' , A' , adjacent to the opening, are 90 secured in like manner, by plate b and bolts b' , b'' . The bolt b' is extended upward to and through the plate C, on one side of the opening and through the plate C' on the opposite side of said opening, and the chairs 95 B, B' , respectively, are suspended by said bolts from said plates. b''' represent nuts which are mounted on the respective bolts b' , b'' , and are turned down on to the plates 100 b , b , to rigidly hold said plates on the lower flanges of the rails A, A', respectively. At crossovers of the track the members C, C' are preferably continued across the opening in the track, as is indicated by broken lines C'', Fig. 1; but where the track passes through a door way the portion of said members indicated by the broken lines C'' is omitted, so as to present no obstruction to a door being closed through said opening.

105 B'' , B''' , represent additional nuts on bolts b' , b'' , by means of which the bolts are rigidly secured in place in members C, C'. D, 110

D', represent bolts which are respectively pivotally mounted on pins d , d' , in members E, E'. F, F', respectively represent rail sections which are normally in a vertical position, and are pivotally mounted intermediate the length thereof on pins e , e' , respectively, and said pins extend through the members G, G', which are secured on the upper ends of members D, D', respectively, as by screw threads indicated by broken lines in Fig. 1, and the set nuts g , g' , respectively. H, H', represent abutments which are mounted in members G, G', respectively, and h , h' , represent abutments with which abutments H, H', are in contact when standards D, D', and rails F, F', are in normal position. These abutments H, h , and H', h' , permit the rail sections F, F' to swing on pivots e , e' , respectively, away from the opening in the track, when a trolley wheel (X, Fig. 4) comes against said rails after leaving the horizontally positioned track section bridging the opening in the track; as is illustrated in Fig. 4. When the rails of a track section are forced downward, around the pin d , (or d'), into a horizontal plane, as indicated by broken lines in Fig. 1 and illustrated by full lines in Fig. 4, said abutments H, h , and H', h' , co-act to prevent turning of said rails on pins e , e' , and force standards D, D', respectively, to turn synchronously with said rails into a horizontal plane. I, I', represent barrels which are rigidly secured in place on members C, C', respectively. Members I, I', respectively contain a spiral spring, (i), and J, J', respectively represent cables which are secured at one end, as by eye-bolt j , to members G, G', and at the other end are connected to said spring so as to be held taut; and when the track section F, (or F'), is turned down, (together with standard D, or D'), into a substantially horizontal plane, to bridge the opening between track ends a , a' , said spring is put under additional tension, (or wound up), and when the weight of a trolley crossing said rail or track section is removed therefrom, by travelling off the section, said spring automatically returns members D (or D'), and F, (or F'), to normal position. K, K', respectively represent stops mounted on bolts b , b' , against which the upper ends of the rail section members abut, when said members are returned to normal position by spring i and cable J, (or J'), as last above set forth.

The operation of the apparatus is as follows: Assuming a trolley wheel (X, Fig. 1), to be moving on track or rail A, toward the opening in the track; said trolley wheel will come into contact with the vertically positioned track section F, and will turn said track section, together with the verti-

cal member D, (said member D turning on pin d) into a substantially horizontal plane, as indicated by broken lines in Fig. 1, and illustrated by full lines in Fig. 4; and said trolley wheel X may continue its travel toward the right and along the rail F, while said rail is in a horizontal plane. As said trolley wheel X, leaves said track section, (as indicated in Fig. 4), it comes in contact with rail F', turning said rail on pivot e' sufficiently (in its forward travel) to pass under said rail (see Fig. 4). As said trolley wheel leaves said horizontally positioned track section the spring i and cable J return it to a vertical and normal position, and as said trolley wheel moves from under the track section D', said section will fall, by gravity, into a vertical and normal position.

When a trolley wheel approaches the opening in the track from the right hand side thereof as viewed in Fig. 1, the track F' and bolt member D' are turned into a horizontal plane bridging the opening in the same way track F and bolt member D are turned by the trolley wheel in to a horizontal plane as last above described.

I claim:

1. A two part member normally in a vertical position, one of said parts pivotally mounted adjacent to an opening in a suspended track rail at the lower end of said part, and the other part comprising a rail forming a track section, pivotally mounted intermediate its ends on said first named pivotally mounted part, projections on said parts arranged to coact and to permit rotation of said track section on its pivot in one direction and to prevent its rotation on said pivot in the other direction.

2. In a suspended track rail having an opening between the ends of rails forming elements of said track, and two part members, one of the parts of each of said two part members pivotally mounted adjacent to said ends of the rails, and the other of said parts comprising rails forming track sections adapted to bridge said opening and pivotally mounted intermediate of the ends on said pivotally mounted parts, in combination with abutments on said parts arranged to co-act to permit rotation of said track sections in one direction on the pivots thereof, and to prevent rotation thereof in the opposite direction.

3. In a suspended track having an opening between the ends of rails forming members of the track, in combination with two part members, one of said parts of each of said two part members pivotally mounted adjacent to said ends of the rails and the other of said parts comprising a rail forming a track section adapted to bridge said opening and pivotally mounted intermediate of the ends thereof on said pivotally mounted

part, abutments on said parts arranged to co-act to permit rotation of said track sections in one direction on the pivots thereof, and to prevent rotation in the other direction, and means to yieldingly maintain said two part members normally in vertical position with said opening not bridged thereby and to obstruct the rails approaching said opening.

10 4. In a suspended rail track provided with an opening, members pivotally mounted adjacent to said opening, rail sections pivotally mounted on said members, abutments on said members arranged to co-act 15 and to permit said rail sections to turn pivotally away from said opening, the rails of said rail sections arranged to obstruct the trolley wheels of trolleys approaching said opening and to be turned, together with 20 said first named member into a substantially horizontal plane and bridging said opening by the advance of said trolley, all combined as set forth.

5. In a suspended rail track provided 25 with an opening, members pivotally mounted adjacent to said opening, means to yieldingly hold said members normally in a substantially vertical position, track sections pivotally mounted on said members, means 30 to prevent said track sections turning in one direction on said pivots and to permit them to turn in an opposite direction, said track sections arranged to obstruct the rails approaching said opening and, together with 35 said first named members, to be turned by trolley wheels of a trolley approaching said opening from said normal position to a sub-

stantially horizontal position bridging said opening, and said track section arranged to be turned on the pivot thereof by the wheels 40 of a trolley leaving said track section, to permit said wheels to pass thereunder.

6. In a suspended rail track, chairs suspended in spaced relation, rails, the ends thereof supported on said chairs, abutments 45 on said chairs and members pivotally mounted in said abutments, in combination with means to yieldingly hold said members normally in a vertical position and to return them from a horizontal to said vertical position, track sections pivotally mounted on said members, means co-acting to permit rotation of said track sections on the pivots thereof by the wheels of a trolley travelling 50 in a determined direction and to prevent rotation of said track section by the wheels of a trolley travelling in an opposite direction, whereby the wheels of a trolley travelling in said determined direction may pass under said track section, and the wheels of a 55 trolley travelling in the opposite direction will force said track section and said pivot ed member into a substantially horizontal plane bridging the opening between the 60 ends of the rails which are mounted in said spaced relation on said chairs and said track section arranged so that the ends thereof rest on said chairs when bridging said opening.

NIC KRUMP.
